UNITED STATES PATENT OFFICE.

WILLIAM L. BROOKE, OF OAKLAND, CALIFORNIA.

MEAT AND BONE CUTTING MACHINE.

1,321,882.

Specification of Letters Patent. Patented Nov. 18, 1919.

Application filed May 20, 1919. Serial No. 298,525.

To all whom it may concern:

Be it known that I, WILLIAM L. BROOKE, a citizen of the United States, residing at Oakland, in the county of Alameda and State of California, have invented a new and useful Meat and Bone Cutting Machine, of which the following is a specification.

My invention relates to improvements in meat and bone cutting machines, and the objects of my invention are to provide a power driven saw blade for use in meat markets, or shops, and so constructed as to be readily fixed to any meat block, table, bench or other stable support, to be of quick and easy control and noiseless in its operation. I attain these objects by the mechanism illustrated in the accompanying drawing, forming a part of this specification, in which:

Figure 1 is a side elevation, and
Fig. 2 is a plan of the structure.

Fig. 3 is a vertical section of part of the machine along the line A—B in the plan, drawn to a larger scale.

Similar numerals designate similar parts throughout the different views.

The form and dimensions of various parts of the machine may be changed without interference with their respective functions.

In the drawings the uppermost part of a meat block or table is delineated, but, as the meat block or other support is not a part of my invention, it need not be considered further than to indicate the relative position of the saw frame.

A bracket 2 formed with an upright hollow post thereon is fixed to the side of the meat block 1 by means of lag screws or otherwise. A post-head or cap 3, having a spindle turned thereon and adapted to form a socket union with the hollow post, and revolute thereon, carries the saw frame, the post-head or cap 3 having a hinge connection with the tail-piece 4, the axis of the hinge joint being horizontal and at right angles with the line of the arm 12.

A tubular arm 12 supported at its inner extremity by a sleeve clamp connection with the tail-piece 4 comprises the principal member of the saw frame.

A hanger 13 is connected with, and supported by, the arm 12 near its outer end by a

sleeve adapted to slide along the arm 12. The lower end of the hanger 13 is bent outward horizontally and forked and this fork supports vertically a cylindrical casing 14, the casing 14 being hinged at its lower end to the legs of the fork, the axis line of the hinge joint being horizontal and at right angles with the longitudinal line of the arm 12.

The casing 14 has anti-friction bearings 60 fitted into and inclosed at each end, the casing 14 being enlarged sufficiently to form cups for the bearings.

A shaft extends longitudinally through the casing 14 and is supported by the anti-friction bearings lodged within the casing 14. The shaft is extended downward and outward from the casing 14 and a wheel, or pulley, 19 is firmly fixed to and upon the lower end of the shaft. The upper end of 70 the shaft is extended into a slot formed in the under side of the sleeve of the hanger 13, the width of the slot being a trifle greater than the diameter of the shaft. The slot extends lengthwise with the sleeve and is of 75 sufficient length to allow a certain amount of forward or backward inclination of the shaft and its supporting mechanism; i. e., the casing 14 and the anti-friction shaft bearings inclosed therein.

An electric motor 7 is fixed to and supported upon a base plate 6 axially hinged to the tail-piece 4, the axis line of the hinge joint being horizontal and at a right angle to the longitudinal line of the arm 12. This 85 hinge connection and its purposes are hereinafter set forth.

The armature shaft of the motor 7 is extended downward and a pulley 19^a is fixed to and on the lower end of the shaft, the 90 pulley 19^a being adjusted to rotate in an approximately horizontal plane.

A depending bracket 11 is connected to the arm 12 by means of a sleeve clamp formed on the bracket 11 and this bracket 11 carries two branches or limbs 10^b—10^c extended outward and at right angles to the arm 12 and bent downward and forked at the outer ends. The limbs 10^b—10^c are joined to the bracket 11 in a socket connection, the 100 bracket 11 having a hollow lug on either side into which the upper end of the limb is

inserted, and retained by means of a set-screw.

A bracket 9 having a sleeve clamp connection with arm 12 carries two branches or limbs 10—10^A joined to the bracket 9, the limbs extending outward and downward and having a forked extremity. The limbs 10—10^A are connected to the bracket 9 and held in position in a manner similar to that specified in relation to the bracket 11 and its dependent limbs.

A band saw blade 20 trained upon the pulleys 19—19^A comprises the cutting member of the machine.

15 The pulley 19^A rotating in conjunction with the motor shaft actuates the saw blade 20.

A guard or fender 18 hung to the forked extremities of the bracket limbs 10—10^A—20^B—10^C and adjacently skirting that part of the saw blade 20 not used for cutting, prevents contact with the saw blade except as required in its operation.

25 A sheave 23 mounted on a fork of the bracket limb 10 and a sheave 23^A carried by a fork of the bracket limb 10^B, serve to keep the saw blade 20 in contact with the meat or bone and to guide the blade while in operation.

30 A hollow grip or hand-hold 16 fitted to the outer extremity of the arm 12 may contain a suitable switch mechanism properly insulated and adapted for operation by finger pressure exerted upon a lever trigger

35 17 fitted in a slot in the under side of the grip 16. The switch is connected with insulated wires inclosed in the arm 12 and extended therefrom to the motor 7 and to any convenient outlet. The motor structure and 40 its wire and switch accessories constitute no part of my invention, as any adaptable motor and switch device may be utilized; but the location of the switch and the manner of its control, as specified, should be considered as important elements in its operative usefulness.

50 As a band saw blade will not continuously adhere to flat faced pulleys rotating in a true common plane, approximately horizontal, a means of adjusting the pulleys to such planes of rotation as may be required must be provided. Therefore, in my invention I have incorporated the hinge connection of the motor base 6 with the tail-piece 4, and the hinge connection of the casing 14 with the hanger 13, as above specified. By means of these hinge connections each of the pulleys 19—19^A may be adjusted to rotate in a plane of its own and at such angle of variance with the other as may be required to retain the saw blade 20.

55 A thumb-screw 22 fitted in the hanger 13 and in connection with the head of the casing 14 holds the pulley 19 in its plane of

rotation, and the thumb-screw 8 fitted into 65 a lug on the periphery of the base plate 6 in connection with the tail-piece 4 serves a like purpose in relation to the pulley 19^A.

60 By means of the thumb-screw 15, fitted in the bracket 11 and acting upon the hanger 70 13, the saw blade may be adjusted to a proper degree of tension.

75 The specified manner of mounting the machine affords a universal movement of entire saw frame.

The machine may be assembled and attached to the meat block in a manner to suit the convenience of either a right or left handed operator, the only necessary change being a transfer of the fender 18 and the 80 sheaves 23—23^A, and their supporting members from one side of the arm 12 to the opposite side.

In operation the saw blade 20 is brought 85 into position directly above the material to be cut, the motor is started by finger pressure upon the trigger 17 followed by a downward movement of the arm 12 which forces the actuated saw blade 20 through the meat or bone.

90 The operation of my invention is not attended by the objectionable noises incidental to machines of this class, as the drive pulley is connected with and forms practically a working part of the motor, thus dispensing 95 with all gear, chain, or other intermediary saw driving connections.

Having described my invention, I claim:

1. In a meat and bone cutting machine, a 100 frame revolvably mounted on a base and carrying an electrical motor and a band saw blade trained upon two pulleys, one of said pulleys being fixed to and coactive with the armature shaft of the motor, as described.

2. In a meat and bone cutting machine, a 105 saw frame consisting of a tubular arm with a detachable tail-piece extension supported by and revolvble upon a base, an electrical motor carried upon a tilting base plate supported by the extended tail-piece of the arm 110 and having a driving pulley fitted to the armature shaft thereof, a fellow pulley fixed to a shaft supported by a hanger having connection with the arm by a slidble sleeve, a band saw blade trained upon said pulleys 115 and adapted to effect a vertical cleavage.

3. In a meat and bone cutting machine, the combination of a tubular arm having a tail-piece affixed thereto and having a hinged connection with a supporting revoluble post, 120 an electrical motor carried upon a base plate in hinged connection with the tail-piece of the arm and having a driving pulley fixed to the armature shaft thereof, a fellow pulley fitted to a shaft supported by bearings 125 lodged within a cylindrical casing having a hinge connection with a hanger supported by the arm by means of a slidble sleeve, a

band saw blade encompassing the pulleys and arranged to effect a vertical cleavage, brackets clamped to the arm and having detachable and adjustable limbs supporting a fender in proximity to the unused part of the saw blade and sheaves to hold the saw blade in alinement and oppose the upward pressure against the saw blade while cutting,

a thumb-screw medium of adjusting the saw blade to a proper degree of tension, a thumb-screw bonding the base plate of the motor and the tail-piece, and a similar connection between the cylindrical casing and its supporting hanger as adjustment mediums.

WILLIAM L. BROOKE.
